LIGHTING FIXTURE FOR WALLS OR THE LIKE

Joseph Bruno, 71 Long Vue Ave.,
North Providence, R.I. 02904

Filed Apr. 4, 1968, Ser. No. 11,305

Term of patent 14 years

U.S. Cl. D48—4
Int. Cl. D26—02

FIG. 1

FIG. 4

FIG. 3

FIG. 5

FIG. 2

FIGURE 1 is a perspective view of lighting fixture for walls or the like according to the present invention;

FIGURE 2 is a partially exploded transverse sectional view thereof;

FIGURE 3 is a side elevational view thereof;

FIGURE 4 is a bottom plan view thereof;

FIGURE 5 is a view as seen when looking in the direction of the arrow shown in FIGURE 2.

The opposing ends are identical in appearance. The essential features of the invention consist of those portions shown in full lines.

I claim:

The ornamental design for a lighting fixture for walls or the like, substantially as shown and described.
